APPARATUS FOR ELECTROPLATING.

1,319,029.

Specification of Letters Patent. Patented Oct. 14, 1919.

Application filed November 4, 1915. Serial No. 59,501.

To all whom it may concern:

Be it known that we, GERHARD T. POTTHOFF and KURT T. POTTHOFF, citizens of the United States, residing in the city of New York, borough of Brooklyn, county of Kings, State of New York, have jointly invented certain new and useful Improvements in Apparatus for Electroplating, of which the following is a specification.

10 This invention relates to electro-plating apparatus for commercial use on a large scale and the object is to provide means to permit the ready electro-plating of a number of articles simultaneously, whereby said articles may be readily immersed in and removed from the electrolyte or bath, and our invention has particular reference to galvanizing, by the electrodeposit of zinc, a plurality of pipes simultaneously, as for 15 conduits to contain electric conductors; a further object is to improve the quality of the manufactured product, to provide greater durability and uniformity of plating, and to accomplish the purposes more 20 economically than heretofore.

This improved apparatus, when used to plate tubes and pipes, includes, a tank, preferably in the form of a quadrilateral, of suitable dimensions. Said tank is supplied 25 with a suitable electrolytic liquid, and has a conveyer or endless belt continuously advancing and extending within the tank. The links of said conveyer carry tapering spindles each adapted to enter the end of a pipe 30 or tube and snugly fit therein; the pipe is thus supported transversely in its passage through the tank. The spindles are suitably spaced apart and project in such manner as to immerse the articles to be plated in 35 the solution. The free end of each pipe may be closed by a plug formed of or equipped with magnetic metal whereby when a pipe reaches the end of its travel at the end of the tank, it may be automatically pulled 40 off its spindle and automatically transferred to a rinsing tank, first passing through a draining tank. Each spindle is rotated on its axis during its passage from one end to the other in the tank containing the solution 45 and by reason of the motion of translation and the motion of rotation the pipe is uniformly coated.

To increase the capacity of the plating apparatus we provide for carrying two parallel lines of pipes on a single conveyer and to avoid any interference with the plating

operation we support each pipe by interior contacts or engagement, like the spindle at one end and the plug at the other end, and thus guard against any interference with 60 the plating operation or any mechanical or electrical interference with the exterior of the pipe being plated.

When a pipe or pipes reach the end of travel it or they are withdrawn or disconnected at the spindle end, and a pair of arms are projected to receive the plated pipe or pipes, the arms are tilted and the pipes are deposited in a draining tank in which wheels, having projecting, radially arranged spokes or arms, transfer the tubes or pipes to a rinsing tank in which similar wheels, all rotating in the same direction, deliver the pipe. An operator may next remove the aforesaid plug or plugs when 75 used.

The accompanying drawings illustrate the invention.

Figure 1 is a top plan view; Fig. 2 is a longitudinal sectional view just inside the 80 wall of the tank at the conveyer end; Fig. 3 is a transverse section at the exit end showing the means for disconnecting the pipe from its spindle; Fig. 4 is a sectional view showing the arrangement for advancing the 85 conveyer and for rotating the spindles; Fig. 5 is a detail view of the spindle with its packing; Fig. 6 is a detail showing the means for advancing the conveyer and supporting the spindle, taken at right angles to 90 that appearing in Fig. 4; Fig. 7 shows the electro-magnetic means for detaching a pipe from its spindle at the end of its travel with the arms for supporting the pipes and transferring them; Fig. 8 shows a detail of the 95 electro-magnetic disconnecting device for the pipe, and Fig. 9 shows the plug with means for expanding it within the tube, and the head of electro-magnetic material forming part of the plug.

In Fig. 1, *t* indicates a suitable tank adapted to contain an electrolytic solution. Arranged transversely at the top of the tank in place for supporting purposes, bars like 10 are located. The bars 10 support anode plates *a* at a suitable point within the solution, which plates are preferably insulated from the bars 10 when the latter are of metal. At *b* are anode plates shown supported on longitudinal metal bars 30 that 110 are shown supported on insulating rails 31 on the bottom of the tank. At 11 are metal

bars, preferably of copper, shown longitudinally arranged with respect to the tank. Said bars 11 are suitably supported, as by brackets from the bars 10, the bars 11 being suitably insulated from the bars 10 when the latter are made of metal. We have shown a linked conveyer comprising two parallel chains 12 and 13, and at suitable intervals along the conveyer 10 are brackets *c*, shown having cross bars 14 connecting the chains 12 and 13. Said brackets are in electrical circuit with bars 11 and the cross bars 14 are slideable upon the bars 11, said conveyer serving as a support for said brackets. The chains of the conveyer are shown passing over suitable sprockets whereby the chains may be guided and rotated. Each bracket carries a bearing for a spindle, such as a pair of bearings like 15 and 16, Fig. 4, and between them is a bearing 17. The spindles *s* are to be rotated as the conveyer advances, for which purpose we have shown each of the bearings 15, 16 and 17 supporting a rotative wheel 19, 20, 21, the wheels 19 and 20 being connected to spindles *s*. These spindles are tapering and are adapted to snugly fit the interior of the tube or pipe *x*, the fit being such as to enable the spindle to support the tube and to admit the easy withdrawal of the tube. Means are provided to rotate said wheels, for which purpose we have shown a rack bar 22 engaging the wheels 20, as the latter advance. This causes the spindles to rotate and the third gear 21 causes both spindles to rotate in the same direction. On the side of the tank is a grooved bar 23 fixed in position to engage with a steadyng roller 24, there being one such roller for each bracket *c*. At the opposite side of the tank there are angle bars 25 fixed on the wall adapted to support the corresponding ends of the pipes *x*. We have shown said bars 25 in position to engage with disks 26 of magnetic metal in the nature of armatures, fixed on the plugs 27 adapted to be fitted to the adjacent ends of pipes *x*. Plug 27 is provided with a sleeve 28 having a tapering head to engage with the interior of the free end of the tube *x*. The sleeve 28 is screw-threaded to engage with a screw thread on the plug 27; sleeve 28 is split and engages with a tapering expander 29 which is tubular and screw-threaded to engage with the screw thread on plug 27, the arrangement being such that expander 29 will operate to open the sleeve 28 when the disk 26 is rotated to temporarily secure the plug and disk to tube or pipe *x*. The plug section 28 is preferably of non-conducting material and the gear wheels 19, 20, 21, are also of non-conducting material, as is the rack or rail 22. The metal bars *a* and *b* are electrically united and connected to the positive terminal of the dynamo *d*. The negative pole of the dynamo is connected to the

bars 11. It is to be noted that the brackets *c* are covered and protected by insulating material and on the spindle *s* as shown in Fig. 5 there is a bushing 33 of insulating material. The spindle *s* is provided with a packing 34 and is held in position by a set screw 35 taking in a groove 36 in the shaft of the spindle.

After the termination of the electroplating of the pipes, as at the end of the movement of translation the pipes are removed by disconnecting them from the carrying spindles *s*. To automatically remove the pipes or tubes from the spindles we have shown an electromagnet 40 located on a reciprocating shaft 41, operated by a cam 42. A dynamo 43 is connected in circuit with the winding of the magnet 40 and with brush terminals 44 and 45. On the surface of the cam wheel 42 there is a strip of conducting metal 46 which electrically unites the brushes 44 and 45 for approximately one-half rotation of the cam or eccentric 42. This operates to close the circuit through the magnet as the attraction of the magnet is sufficient to detach the pipe or pair of pipes from the spindles supporting them, when the cam or wheel 42 causes appropriate operation of rod 41. Immediately the pipes are detached from the spindles the pipes drop upon a pair of arms 50, 51 that are pivoted at 52, 53, and are connected by a bar 54, that is shown slotted at 55 and 56. A pin 57 connects the arm 50 to the slot 55 and the pin 58 connects the arm 51 with the slot 56 in bar 54. The bar 54 is connected with the reciprocating member 59, carried on the reciprocating arm 41, and the connection between 54 and 59 is such that the position of the arms 50 and 51 at one limit of the movement of the reciprocating rod 41 is that shown in full lines, while that at the opposite limit of rod 41 is shown in the broken line position, (Fig. 7). It results from the construction shown and described that when the magnet 40 attracts the pipes or tubes as by attracting the disks 26 of magnetic material, the arms 50 and 51 are in the full line position, and as soon as the pipes or tubes are detached from the spindles at the initiation of the return movement of the magnet 40, that is the retraction of the magnet 40, a pipe or pair of pipes drop on to the arms 50 and 51 when the circuit of the magnet is broken, and are caused to roll into position between a pair of spokes 61 on the wheel 60 in the draining tank 62. The arms 50, 51 are moved laterally to permit the pipes or tubes to rise from the electrolyte and are then moved under the pipes or tubes to direct the latter into tank 62, and so on successively. Wheel 60 rotates counter-clockwise and the pipes are moved together into position where they are projected upon the in-

clined plane 64' connecting draining tank 62 with rinsing tank 63. In the rinsing tank 63 there are wheels 70 similar to wheel 60. The wheels 70 have regularly arranged 5 spokes 71. The free ends of these spokes travel close to a curved surface 72 and the pipes are rolled along on this surface 72 through the rinsing liquid and are projected out upon the floor. In the draining tank 10 62 there is a curved surface 64 arranged like the surface 72 in tank 63.

We have shown the part 64 in drain tank 62, in the form of a strip, but it may be found better to use a plurality of strips, 15 like 64, and uniformly space them.

What we claim is:

1. In an electro-plating apparatus, the combination, with the plating apparatus, of a conveyer, a series of tapering spindles 20 supported at right angles to said conveyer, a pinion on each spindle, and a rack bar fixed along the lower run of said conveyer arranged to mesh with said pinions.

2. In an electro-plating apparatus, the combination, with the tank, the liquid and 25 electric circuit, of a reciprocating electro-magnetic device, a series of armatures, one for each object plated, a circuit for said magnet, and means for opening and closing 30 said circuit at predetermined intervals.

3. In an electro-plating apparatus, the combination of a tank, electrolytic liquid in the tank, a linked conveyer, a plurality of 35 spindles supported upon said conveyer, means for rotating the spindles, and means for automatically removing the object coated from a spindle at a predetermined point in its movement.

4. In an electro-plating apparatus, the combination of a tank, electrolytic liquid, a linked conveyer, a plurality of supporting 40 devices arranged upon said conveyer, means for rotating each supporting device and means for automatically releasing the 45 objects plated at a predetermined point.

5. In an electro-plating apparatus, the combination with the plating apparatus, of means for automatically removing the plated 50 object to a position outside the plating tank including an inclined plane normally out of position and a device to change the position of said plane.

6. In an electro-plating apparatus, the combination, with the plating apparatus, of 55 means for automatically and positively moving the object plated to a position outside the plating tank including a plane supporting surface normally out of position and a device for reciprocating said surface.

60 7. In an electro-plating apparatus, the combination, with the plating apparatus, of electro-magnetic means for automatically and positively detaching the object plated and a device for transferring said object 65 to a position outside the plating tank con-

sisting of a support and means for changing the position of said support.

8. In an electro-plating apparatus, the combination, with the plating apparatus, of a magnetic member connected with the object to be plated, an electro-magnet, a reciprocating support for the magnet, and means for causing the magnet to engage with said magnetic member and remove the object at a predetermined point. 70

9. In an electro-plating apparatus, the combination of a holder for the object to be plated, a reciprocating device for automatically and positively detaching the object plated, an inclined plane, normally out of 75 position, adapted to receive the detached object, means for changing the position of said plane to receive the detached object after its release, and means whereby the operation of said detaching device controls the position 80 of said inclined plane.

10. In an electro-plating apparatus, the combination, with the plating tank including the liquid, the anode, the circuit, and a conveyer, of means for detaching objects 90 supported on said conveyer successively, said means consisting of an electromagnet, a circuit therefor and means for making and breaking said circuit at predetermined points in the movement of the conveyer. 95

11. In an electroplating apparatus, the combination of a tank, an electroplating circuit and the liquid, of a conveyer having two lines of supporting devices whereby two rows of objects are supported in parallel, horizontal planes within the liquid and gradually moved from one end of the tank to the other.

12. In an electro-plating apparatus the combination, with a tank, an electro-plating circuit and the liquid, of a conveyer having supports for a series of tubes consisting of a series of rotary spindles arranged transverse to the line of conveyer movement, said supports engaging each tube at one end thereof and translating it, within the liquid, from one end to the other of said tank.

13. In an electroplating apparatus, the combination with the tank, the solution, an electric circuit and a conveyer, of a series of tapering spindles carried by said conveyer, each of said spindles adapted to enter the end of a tube and support said tube in its passage from one end of the tank to the other.

14. In an electroplating apparatus, the combination with the tank, the solution, an electric circuit and a conveyer, of a series of tapering spindles carried by said conveyer, each of said spindles adapted to enter the end of a tube and support it in a horizontal plane, and a device to engage and detach said tubes in succession.

15. In an electroplating apparatus, the combination with the tank, the solution, an

electric circuit and a conveyer, of a series of tapering spindles carried by said conveyer, each of said spindles adapted to enter the end of a tube and support it in a horizontal 5 plane, and a device to engage and detach a plurality of said tubes, successively.

16. In an electroplating apparatus, the combination of a tank, an electric circuit, a conveyer, means on the conveyer to engage 10 objects to be plated, a bar carried by the tank, disks to travel on the bar, and means to attach the disks to said objects for supporting their adjacent ends on the bar.

17. In an electroplating apparatus, the 15 combination of a tank, an electric circuit, a conveyer, means on the conveyer to engage objects to be plated, a bar carried by the tank, disks to travel on the bar, and expanding means connected with the disks 20 to co-act with said objects to connect them with the objects.

18. In an electroplating apparatus, the combination of a tank, an electric circuit, a conveyer, brackets carried by the conveyer,

means carried by the conveyer to co-act with 25 objects to be plated, and a bar to slidably co-act with the brackets.

19. In an electroplating apparatus, the combination of a tank, an electric circuit, a conveyer, brackets carried by the conveyer, 30 rotative means carried by the conveyer to co-act with objects to be plated, means to rotate said last named means, a bar to slidably co-act with the brackets, and means to steady the brackets as they travel with the 35 conveyer.

20. In an electroplating apparatus, the combination of a tank, an electric circuit, a conveyer, brackets carried by the conveyer, 40 rotative means carried by the conveyer to co-act with objects to be plated, means to rotate said last named means, a bar to slidably co-act with the brackets, a bar carried by the tank, and means on the brackets to co-act with the bar as the 45 brackets travel.

GERHARD T. POTTHOFF.
KURT T. POTTHOFF.
